UNITED STATES PATENT OFFICE.

FRANZ TRINKS, OF BRUNSWICK, GERMANY.

CALCULATING-MACHINE.

1,160,015.

Specification of Letters Patent.

Patented Nov. 9, 1915.

Application filed February 26, 1914. Serial No. 821,202.

To all whom it may concern:

Be it known that I, FRANZ TRINKS, manufacturer, citizen of the Duchy of Brunswick, Empire of Germany, residing at Brunswick, Germany, have invented certain new and useful Improvements in Calculating-Machines, of which the following is a specification.

My invention relates to improvements in calculating machines, and more particularly to the spring actuated detent mechanism for holding the numeral wheels of the registering mechanism in correct position. In machines now in use the said detent mechanism consists of spring actuated levers which engage in the teeth of the spur gears connected with the numeral wheels. If it is desired to reset the numeral wheels the said levers must be thrown out of engagement with the spur gears, for which purpose they are rocked together with their springs in a radial direction away from the spur gears. This construction is objectionable in so far as it requires much room, so that certain detent mechanisms cannot be used, especially such as consist of a rocking lever having its opposite arms engaging alternately in the teeth of the spur gears. More particularly this detent mechanism cannot be used in calculating machines in which the registering mechanism is mounted on a slide which is adapted to be shifted in a direction parallel to the shaft of the setting mechanism, for which reason in machines of the type specified detent mechanism of a more simple and less effective construction has been provided. Apart from this when rocking the detent elements radially the throw of the said elements which corresponds to the height of the teeth is comparatively large.

The object of the present improvements is to provide a detent mechanism of this class in which this objection is avoided.

With this object in view my invention consists in so mounting the detent mechanism that for throwing it out of engagement with the spur gears it is shifted in a direction parallel to the axis of the numeral wheels. Thereby I am enabled to utilize a detent mechanism of any preferred construction, and more particularly a detent mechanism in which the detent consists of a rocking lever having two arms which alternately engage in the teeth of the spur gears connected with the numeral wheels. When thus constructed the throw of the mecha-

nism for shifting the detents out of operative positions relatively to the numeral wheels is very small, and as a matter of fact it is only a little more than the breadth of the teeth of the spur gears.

For the purpose of explaining the invention several examples embodying the same have been shown in the accompanying drawings, in which the same letters of reference have been used in all the views to indicate corresponding parts.

In said drawings Figure 1, is a front view partly in section showing a calculating machine in which the detents for the numeral wheels consist of rocking levers, and in which the setting mechanism consists of setting disks having radial teeth which are adapted to be shifted by cam disks into or out of operative positions, Fig. 2, is a cross-section of Fig. 1, Fig. 3, is a detail view partly in section showing a modification of the detent mechanism, Fig. 4, is a cross-section of the carriage carrying the registering mechanism of a calculating machine provided with a modification of the detent mechanism, and Fig. 5, is a side view of the said carriage with all the numeral wheels removed.

Referring to the example illustrated in Figs. 1 and 2, my improved calculating machine consists of setting disks p which are mounted on a shaft p^2 adapted to be rotated from a crank q by means of gear wheels q^1 and q^2 . For setting the desired number of teeth on the setting disks cam disks p^1 are provided. The teeth of the setting disks are arranged to engage intermediate gear wheels r mounted on a shaft r^1 and adapted to impart rotary movement to gear wheels b connected with numeral wheels c , as is shown in Fig. 2. The numeral wheels c are loosely mounted on a resetting shaft g ; and the said resetting shaft and the shaft r^1 are mounted on a carriage s which is slidable in a direction parallel to the shaft p^2 of the setting mechanism. On the said carriage and coaxially of the registering mechanism c a revolutions counting mechanism t is provided which is adapted to be operated from the shaft p^2 of the setting mechanism by means of a single tooth v , as is shown in Fig. 1.

The numeral wheels c are adapted to be rotated with a step-by-step movement which is caused by the operation of the disk p . To prevent any excess movement of the gear b

so that the proper and correct numbers will not be incorrectly displayed through a suitable peep hole in the machine, this step-by-step movement of the numeral wheels *c* is controlled or governed by the rocking detent levers *a* having two arms which are held by springs *d* in engagement with the gears *b* of the numeral wheels *c* and which are mounted on a common shaft *e*. The rounded or enlarged end 6 of the detent *a* is adapted to engage between the teeth of the gear *b* and to be moved downwardly against the tension of the spring *d* upon rotation of said gear *b*, which movement throws the opposite locking end 7 thereof into engagement with the teeth of the gear *b* and thereby completely and positively arrests the rotating motion of said gear. As soon as the tooth of the gear *b*, which has just engaged with the end 6 of the detent *a* and operated the same to move downwardly, has passed said enlarged end, the spring *d* expands and moves the end 7 again between the teeth of the gear *b* whereby the numeral wheel *c* is held in position to properly display the correct number through the peep hole. As shown the said shaft and the springs *d* are mounted on a slide *f* which also provides a bottom support for the springs *d*. The slide *f* is adapted to be shifted in a direction parallel to the shaft *g* of the registering mechanism, and it is normally held with the detents *a* in operative positions relatively to the gear wheels *b* connected with the numeral wheels *c* by a stop *i* and a spring *h*. To the slide *f* a stop member *k* is secured which engages the beveled bottom of a lateral notch *o* in a disk *m* which is connected with or mounted on the shaft *g* of the numeral wheels. Therefore when turning the resetting shaft by means of a wing nut *n* the slide *f* is shifted longitudinally together with the detents *a*, in the direction indicated in Fig. 1 by the arrow *x*. Thereby the detents *a* are thrown out of engagement with the gear wheels *b*. In order that the springs *d* cannot be extended when the detents are thrown into inoperative positions stop members *l* are provided, and in the example illustrated one for each of the detents. The slide is held in inoperative position, until the resetting shaft has completed a full rotation, whereupon the stop *k* is forced by the spring *h* into engagement with the notch *o*, and the detents *a* are shifted laterally and into engagement with the teeth *b*. For throwing the detents into inoperative positions a slight displacement of the slide *f* and of the detents is sufficient, such displacement being equal to the breadth of the teeth of the gear wheels *b*. The detents can be constructed in any known or preferred way.

It will readily be understood, that the means for shifting the slide *f* may be constructed in different ways. In the example

illustrated in Fig. 3 the disk for shifting the slide *f* is mounted at the opposite end of the shaft *g* and it is not provided with a notch but with a projecting cam *o*¹ which engages the slide *f*¹ only in the normal position of the disk *m*¹ and holds the same with the detents *a* in operative positions. The spring acting on the slide has been indicated by the numeral *h*¹.

From the foregoing it will be understood, that the slides *f* and *f*¹ represent examples of means for shifting the detents into and out of operative position relatively to the gear wheels *b*, and that in lieu of the means shown in Figs. 1 to 3 other means may be provided. In order to further demonstrate that my invention is not limited to the constructions shown in the drawings, I have shown in Figs. 4 and 5 an example in which the said shifting means are constituted by a frame connecting all the detents. As represented the shaft *e*² which carries the detents *a*² is shiftable in the side walls *f*² and *f*³ of the carriage *s*¹, and it is connected by side members *u* and *v* with a longitudinal rod *w*, the said parts forming a rigid frame which is shiftable on the resetting shaft *g*². The rod *w* provides a bottom support for the springs *d*² acting on the detents. Axial displacement is imparted to the said frame *e*², *u*, *v*, and to the detents *a*² and the bottom support *w* thereof from the resetting shaft *g*² through the intermediary of a disk *m*² which for this purpose is formed with a cam *m*² adapted to shift the frame in opposition to a spring *h*².

I claim herein as my invention:

1. In a calculating machine, the combination with rotatable numeral wheels, and arresting means, of detents for causing the numeral wheels to rotate with a step-by-step movement and adapted to completely arrest each step movement and hold said wheels in correct positions, and means connected with the arresting means for shifting said detent in the direction of the axes of the numeral wheels to release the latter.

2. In a calculating machine, the combination with rotatable numeral wheels, gear wheels connected with said numeral wheels and resetting means, of detents for successively engaging each tooth of said gear wheels and causing the numeral wheels to rotate with a step-by-step movement, said detents being adapted to completely arrest each step movement of said numeral wheels and hold the latter in correct positions, and means connected with the arresting means for shifting said detents in the direction of the axes of the numeral wheels and out of engagement with the gear wheels.

3. In a calculating machine, the combination, with the numeral wheels adapted to rotate with a step-by-step movement, and resetting means; of spring-controlled, rocking

detents for positively effecting said step-by-step movement and for holding said numeral wheels in correct positions after each successive step-by-step movement; and means connected with said resetting means for shifting said detents in the direction of the axes of the numeral wheels to release the latter.

4. In a calculating machine, the combination with rotatable numeral wheels and resetting means, of detents for causing a step-by-step rotation of said numeral wheels and for holding the latter in correct positions after each step-by-step movement, a slide whereupon said detents are mounted, and a rotary member carried by said resetting means for engaging with said slide to shift the latter and the detents in the direction of the axes of the numeral wheels to release 20 said detents from said wheels.

5. In a calculating machine, the combination with rotatable numeral wheels, and resetting means, of detents for causing said numeral wheels to rotate with a step-by-step 25 movement and for holding said wheels in correct positions after each of said step movements, a shaft upon which said detents are mounted, a slide carrying said shaft, and means connected with said resetting means 30 for shifting the slide and the detents in the direction of the axes of the numeral wheels, to release said detents from said wheels.

6. In a calculating machine, the combination, with the numeral wheels, and resetting 35 means; of spring-controlled, rocking detents for holding said numeral wheels in correct positions; a shaft whereon said detents are mounted; a slide carrying said shaft; and means connected with said resetting 40 means for shifting the slide and the detents in the direction of the axes of the numeral wheels, to release said detents from said wheels.

7. In a calculating machine, the combination, with the rotatable numeral wheels, and resetting means; of detents adapted to engage said wheels and hold the same in correct 45 positions; means for releasing said detents from such engagement; and means for holding said detents in depressed or ineffective 50 positions while so released.

8. In a calculating machine, the combination, with the numeral wheels, and resetting means; of detents adapted to engage said 55 wheels and hold the same in correct positions; means for shifting said detents laterally in the plane of said engagement, whereby the detents are released from such engagement; and means for holding said detents in inoperative position while so released.

9. In a calculating machine, the combination, with the numeral wheels, and resetting means; of rocking detents adapted to engage 60 said wheels and hold the same in correct po-

sitions; means for shifting said detents laterally in the plane of said engagement, whereby the detents are released from such engagement; and means for holding said detents in depressed positions while so released.

10. In a calculating machine, the combination, with the numeral wheels, and resetting means; of detents adapted to engage said wheels and hold the same in correct 75 positions; means for shifting said detents laterally, to release them from such engagement; and stops engageable with said detents when so shifted, to hold them in inoperative position.

11. In a calculating machine, the combination, with the numeral wheels, and resetting means; of detents adapted to engage said wheels and hold the same in correct positions; a movable element carrying said 80 detents; a rotary member carried by said resetting means; and a member carried by said movable element and engageable by said rotary member during its rotation, to shift said movable element and said detents and 85 release the latter from engagement with said numeral wheels.

12. In a calculating machine, the combination, with the numeral wheels, and resetting means; of detents adapted to engage said 90 wheels and hold the same in correct positions; a movable element carrying said detents; a rotary member carried by said resetting means; a member carried by said movable 95 element and engageable by said rotary member during its rotation, to shift said movable element and said detents and release the latter from engagement with said numeral wheels; and means for holding said detents in inoperative position while so released.

13. In a calculating machine, the combination, with the numeral wheels, and resetting means; of spring-controlled, rocking detents adapted to engage said wheels and hold the same in correct 100 positions; a movable element carrying said detents; a rotary member carried by said resetting means; a member carried by said movable element and engageable by said rotary member during its rotation, to shift said movable element and said detents and release the latter from engagement with said numeral wheels; and stops arranged to engage and depress said detents when so released.

14. In a calculating machine, the combination with numeral wheels and resetting means, of spring-controlled rocking detents adapted to engage said wheels and hold the same in correct positions, a movable member carrying said detents, a rotary member carrying said resetting means, and a member carried by said movable element and engageable by said rotary member during its rotation to shift said movable element and said 125

detents and release the latter from engagement with said numeral wheels.

15. In a calculating machine, the combination, with the numeral wheels and resetting mechanism; of spring-controlled, rocking detents arranged to engage said wheels to hold the same in correct positions; means for shifting said detents laterally, to release them from such engagement; and stops arranged to engage and depress said detents when so released.

16. In a calculating machine, the combination, with the numeral wheels and resetting mechanism; of spring controlled, rocking detents arranged to engage said wheels to hold the same in correct positions; a slide carrying said detents and constituting a support for the controlling springs; and means connected with said resetting means for shifting said slide and said detents in the direction of the axes of said wheels, to release said detents from such engagement.

17. In a calculating machine, the combination, with the numeral wheels and resetting mechanism; of detents adapted to engage said wheels and hold them in correct positions; and connections between said resetting means and said detents for automatically

cally releasing the latter during the resetting operation.

18. In a calculating machine, the combination, with the numeral wheels and resetting mechanism; of detents adapted to engage said wheels and hold them in correct positions; connections between said resetting means and said detents for automatically releasing the latter during the resetting operation; and means arranged to engage and hold said detents in inoperative position while so released.

19. In a calculating machine, the combination with rotatable numeral wheels and resetting means, of rocking detents comprising two arms adapted to engage the wheel and to intermittently arrest the rotation of said wheels and hold the same in correct position, and means for shifting said detents laterally to release the latter from said engagement.

In testimony whereof I have hereunto set my hand in presence of two subscribing witnesses.

FRANZ TRINKS.
